UNITED STATES PATENT OFFICE.

ANTONIO DAMORE, OF BROOKLYN, NEW YORK.

PAINTER'S SCAFFOLD.

Application filed December 30, 1925. Serial No. 78,881.

My invention relates to scaffolds of the elevating platform type employed by painters for work on the exterior of buildings. Among the principal objects which the present invention has in view are: the provision of a portable elevating scaffold structure; the provision in such a structure of novel platform supporting and operating means; the provision in a scaffold of this character of novel means for moving a suspended platform horizontally along a building wall; the provision in a scaffold of this character of a novel platform carrier and trackway therefor; and the provision of a safety stop for the carrier.

With these and such other objects in view as will be apparent from the description, my invention resides in the novel combination construction and arrangement of parts hereinafter described and claimed, and illustrated in the accompanying drawings wherein:—

Figure 1 is a fragmentary elevation of the top of a building wall illustrating the scaffold as applied thereto;

Figure 2 is a top plan view of a modified form of trackway and the carrier;

Figure 3 is an end elevation of the scaffold as shown in Figure 1;

Figure 4 is a top plan view of the operator's platform;

Figure 5 is a vertical transverse section therethrough;

Figure 6 is a vertical central section through the platform carrier and trackway;

Figure 7 is a horizontal section on the line 7—7 of Figure 6;

Figure 8 is a fragmentary end plan of the modified form of trackway section of Fig. 2;

Figure 9 is a top plan view of a modified form of trackway section employed for buildings of bowed wall construction.

The scaffold is shown as applied to the wall of a building 10, from the roof cornice 11 of which it is suspended by means of a plurality of substantially arched brackets 12, each of which has a vertical leg 13 provided with angled feet 14 for disposition over the top and edge of the roof cornice as best shown in Figure 3. In service, the brackets 12 are securely fastened to the roofing structure by means of anchor ropes 15 attached to the legs 13 and tied to a suitable roof fixture (not shown). The outer leg 16 of each roof bracket extends downwardly in parallel

spaced relation from the leg 13, having its lower end passed through and riveted to the bottom of a trough shaped track section 17, the upstanding side flanges of which provide rails 18 for the double flanged wheels 19 of a carrier to be subsequently described. The trackway is made up in the desired lengths from a plurality of the sections 17 joined in end to end relation by means of fish plates 20 disposed under the meeting ends of the sections and attached to the respective ends by means of bolts 21. When the scaffold is employed on buildings having bay windows and the like, track sections such as illustrated in Figure 9 are utilized at the desired points. These sections are formed with straight ends 22 and outwardly bowed intermediate portions 23.

The carrier for the operator's seat or movable platform consists of a frame made up of a pair of metal end straps 24 extending transversely between the lower ends of upright arms 25 perpendicular thereto and integral therewith; the straps being connected by a flat metal brace bar 26 disposed in the longitudinal center of the frame and secured at its ends by means of the bolts 27 passed through the bar and straps. Each of the frame arms 25 carries adjacent its upper end an axle bolt 28 over which are journaled the spacer sleeves 29 and carrier wheels 19; the wheels engaging the trackway rails 18 to suspend the carrier therefrom. The inner side of the carrier frame consists of a side bar 30 extending longitudinally of the frame and connected to the inner arms 25 intermediate their ends by fastening bolts 31. The bar 30 is formed with right angled end portions 32 extending for a slight distance transversely of the frame and terminating in extensions 33 projecting beyond each end of the frame and longitudinally thereof. On its outer side the carrier frame is provided with a side bar 34 disposed parallel to and in horizontal alignment with the bar 30 and connected to the outer frame arms 25 by bolts 35. The bar 34 is formed with right angled end portions 36 extending for a slight distance transversely of the frame and terminating in parallel spaced extensions 37 projecting beyond each end of the frame and longitudinally thereof. Pulleys 38 are journaled between the extensions 37.

The upper ends of each side pair of the

frame arms 25 are connected longitudinally of the frame by webs 39 formed integral with the arms so that the arms, webs and straps 24 are an integral unit. Intermediate the arms 25 the webs 39 have attached thereto depending straps 40 formed with inturned fingers 41 which reach from opposite sides of the carrier frame beneath the track 17 forming guards to prevent unseating of the wheels 19.

Secured at its upper end by a nut 42 resting on a bearing formed by the bar 26 of the carrier frame, is the shackle bolt 43 of a pulley block 44 suspended beneath the carrier intermediate the ends thereof. A tackle cable 45 connects the block 44 with a lower pulley block 46 which is in turn connected through a ring bolt 47 with the top bow 48 of an operator's chair or platform 49 consisting of a seat 50 and side pieces 51 connected by rungs 52 with the top side bars 53 and back 54, all of which are securely braced by metal loop straps 55 bound over the ends of the chair. The depending ends 56 of the top bow 48 are rigidly attached to the top side pieces 53 and bottom side pieces 51. A shelf 57 at the rear of the chair provides a receptacle for pots and brushes. If desired, the shelf 57 may be extended to form the seat, providing a receptacle therebeneath.

Spacer rods 58 provided at their free ends with conventional swivelled casters 59 adapted to bear against the building wall, 35 are slidably housed in casings 60 carried by the bottom side pieces of the chair. Set screws 61 extending through the casing walls cooperate with the spacer rods to provide a means for adjusting the spacing of 40 the chair away from the building wall.

The chair 49 is raised or lowered by means of the pull rope 62 of the tackle cable 45, while the chair and carrier are moved longitudinally along the trackway by manipulation of either of the side cables 63 or 45 64. These cables 63 and 64 are guided over the sides of the chair through the eye bolts 65 and 66 fastened in the side pieces 51. The cable 63 is passed over the carrier pulley 38 at one end thereof and continued over a pulley 67 horizontally disposed in a casing 68 secured rigidly to the trackway beneath one end, from which the cable passes to an attachment with the adjacent end extension 33 of the carrier frame. The cable 64 passes over the other carrier pulley 38 and over a pulley 69 horizontally carried in a casing 70 secured under the opposite end of the trackway, after which it passes to an 50 attachment to the other of the carrier end extensions 33. It will be apparent that upon pulling either of the cables 63 or 64, while the other runs free, the carrier and suspended chair may be moved along the trackway 60 across the face of the building wall as de-

sired, the proper elevation having been secured by the elevating block and tackle. The three cables 62, 63 and 64 may be secured in any suitable manner beneath the chair, forming a three point suspension therefor, insuring against dropping of the chair if one of the cables should break.

The pulley casings 68 and 70 are rigidly attached under the opposite ends of the trackway where they project into the path of travel of the carrier providing solid stops against which the carrier pulleys strike to arrest the carrier at the limits of its travel. In the structural arrangement shown in Figure 1 the pulley casings are disposed longitudinally of the trackway, and the carrier stoppage will be to a certain degree abrupt. If pronounced, such an abrupt stoppage may have detrimental effects, such as snapping the cable or overturning paint pots. I have overcome this possibility by providing the modification illustrated in Figures 8 and 2 wherein an end pulley 71 is mounted in a casing 72 which extends laterally outward of the trackway 17. With this construction the carrier moving cable, such as 63, will be angled considerably outward from the trackway end, and as the carrier is securely retained on the trackway, the carrier will be brought to a gradual, yielding stop at the trackway end due to the binding action of the cable and its inherent tensile strength.

While in this embodiment of the invention I have illustrated and described certain details entering into the construction and operation thereof, I desire it to be understood that the invention is not to be limited thereby but that any desired changes and modifications may be made in the structural details as will fall within the scope of the invention as claimed.

I claim:

1. A scaffold comprising a trackway, means for attaching said trackway to a roof structure, a wheeled carrier movable over said trackway, a support suspended from said carrier, a cable associated with said support and attached to said carrier for moving said carrier along the trackway, and a plural element yielding buffer mechanism, one of said elements comprising said carrier attached cable, and another of said elements being secured to said trackway.

2. In a scaffold the combination with a roof attachable trackway, of a carrier comprising a frame having upright side arms, trackway engaging wheels journaled in the upper ends of said arms, side webs connecting the ends of said arms at the top of the frame, derailing guards disposed on said webs and under the trackway, bottom straps connecting the lower ends of said arms transversely of the frame, a brace bar connecting said straps longitudinally of the

frame, a support suspended from said brace bar, and means for moving said carrier along the trackway.

3. In a scaffold the combination with a roof attachable trackway, of a carrier comprising a frame having substantially **U** shaped end members, side webs integrally connecting the upper ends of said members, trackway engaging wheels journaled in said members, side bars connecting said end members intermediate their ends, end extensions formed on said side bars and projecting beyond the frame ends, a bottom brace bar connecting said end members, a support suspended from said brace bar, and means associated with said support and in operative connection with said end extensions for moving said carrier along the trackway.
4. In a scaffold the combination with a trackway, of a carrier comprising a frame having substantially **U** shaped end straps integrally connected at their opposite ends by side webs of a width greater than that of said straps, trackway engaging wheels journaled in the ends of said straps, horizontally aligned parallel side bars connecting said
- straps in spaced relation below said webs, end extensions formed on said side bars and disposed directly under the trackway beyond the frame ends, a bottom brace bar **30** connecting the bottoms of said end straps longitudinally of the frame, a support suspended from said bottom brace bar, and means associated with said support and in operative connection with said end extensions for moving said carrier along the trackway.
5. In a scaffold, a trackway, means for attaching said trackway to a roof structure, a wheeled carrier movable over said trackway, a support suspended from said carrier, a cable having one terminal associated with said support and arranged for moving said carrier along the trackway, and a pulley for said cable carried by said trackway in such manner as to dispose a portion of said cable as a yieldable check on movement of said carrier past a predetermined point.

In testimony whereof I have affixed my **50**
signature.

ANTONIO DAMORE.
